(57) **CLAIM**

The ornamental design for a charging cable, as shown and described.

DESCRIPTION

FIG. 1 is a front perspective view of a charging cable.

FIG. 2 is a top view of the charging cable of FIG. 1.

FIG. 3 is a bottom view of the charging cable of FIG. 1.

FIG. 4 is a left-side view of the charging cable of FIG. 1.

FIG. 5 is a right-side view of the charging cable of FIG. 1.

FIG. 6 is a front view of the charging cable of FIG. 1; and,

FIG. 7 is a rear view of the charging cable of FIG. 1.

In the drawings, the broken lines illustrate portions of the charging cable that forms no part of the claimed design.
